[57] CLAIM

The ornamental design for a needle shield or the like, as shown and described.

DESCRIPTION

FIG. 1 is a perspective view of a needle shield or the like, showing our new design;

FIG. 2 is a side elevational view of the needle shield as viewed from the front;

FIG. 3 is a side elevational view of the needle shield as viewed from the rear;

FIG. 4 is a top plan view of the needle shield of FIG. 2; and

FIG. 5 is a bottom plan view of the needle shield of FIG. 2.

The undisclosed sides of FIGS. 2 and 3 are identical to that shown.
